IMPACT BREAKING OR CRUSHING MACHINES

George Henry Pattinson, "Reslin," Rookery Road, Staines, England

Filed Feb. 2, 1961, Ser. No. 86,688

Claims priority, application Great Britain Feb. 4, 1960
4 Claims. (Cl. 241—285)

The present invention relates to machines for breaking up or crushing stone, gravel, clinker, slag and like material by impact, and concerns those of the rotary type wherein a rotor having a series of radial hammers revolves within a housing or casing having a roughened or ribbed interior surface constituting an anvil against which the material to be broken or crushed by impact is thrown by the heads of the revolving hammers.

The anvil surface may be constituted by blocks made from manganese or other expensive steel and it is an object of the present invention to keep to a minimum the cost of maintaining the anvil surface.

The present invention provides an impact breaking or crushing machine in which a series of attrition resistant blocks is detachably mounted so as to form an anvil surface for the material which is impacted by rotary hammer heads, some at least of the blocks being formed on their striking surfaces with recesses shaped so as to retain some of the crushed or broken material, thereby forming a protecting layer for the anvil surface, and being provided with reverse surfaces which are similar to the striking surfaces and are formed with similar recesses to render the blocks reversible.

Further according to the present invention there is provided, for an impact breaking or crushing machine as hereinbefore defined, an attrition-resistant block formed on its striking surface with a recess shaped so as to retain some of the crushed or broken material, and being provided with a reverse surface which is similar to the striking surface and formed with a similar recess to render the block reversible.

In a preferred constructional form, the two recesses in the blocks are U-shaped and open in opposite directions, thus giving the blocks a cross-section of S-shape. Alternatively, the two recesses may open in the same direction to give the blocks a cross-section of E-shaped and facilitate casting or rolling of the blocks during their manufacture.

Embodiments of the invention will now be described, by way of example, with reference to the accompanying drawings in which:

FIGURE 1 is a sectional elevation showing a breaking or crushing machine;

FIGURE 2 is a detail view showing one of the blocks which form the anvil surface of the machine;

FIGURE 3 is a view in the direction of arrow III of FIGURE 2, and;

FIGURE 4 is a detail section showing an alternative form of block.

The machine described is for breaking or crushing stones, gravel, clinker, slag or the like and comprises a casing 10 within which a rotatable member 11 is mounted. A series of hammers 12, of which the heads 13 are replaceable, are mounted on the rotary member 11. In use, material to be broken or crushed is fed into the hopper 14 and passes downwardly till the revolving hammer heads 13 impact the material against the anvil surface 15. After being broken between the heads 13 and the surface 15 the broken material falls downwardly through outlet 16.

The anvil surface 15 is formed by a series of attrition-resistant blocks 17 formed from manganese steel or other

2

suitable material. Interposed between the blocks 17 are smaller blocks 18 and the blocks 17 and 18 are mounted side by side, forming a stationary arc, and are secured at their ends by means of bolts 19 to the casing 10.

5 It will be noted that each block 17 has a reverse surface which is similar to its striking surface 20 to render the block reversible. The blocks 17 are each formed with two U-shaped recesses 21, preferably to give a cross-section of S-shaped as shown in FIGURE 1. Also, the blocks 18 are formed with longitudinally extending recesses 23 which merge into the recesses 21.

Referring to FIGURES 2 and 3, the block 17 is of elongated form and has at each end a pair of projections 24. The projections 24 are formed with aligned openings 25 for bolts 19 and with lifting lugs 26.

Corresponding bolt holes and lifting lugs are also formed on the smaller blocks 18.

An alternative form of block, 17A, is shown in FIGURE 4. Again, similar recesses 21A render the block reversible but in this case the block has a cross-section of E-shape. As will be appreciated, this section is simpler to cast or roll, during manufacture, than an S-shaped block.

It will be noted that both block 17 and block 17A are symmetrical about the medial plane 28 of the block. The projections 24 are also symmetrically disposed in relation to the medial plane 28. The blocks 17 and 17A have parallel surfaces 29 and 30 and 29A and 30A respectively, which are perpendicular to and intersect the medial plane and form part of the striking surface of the blocks. This arrangement permits the blocks 17 and 17A to be reversibly fitted between the blocks 18.

In operation of the machine, material to be crushed is thrown by the hammer into the pockets formed by the recesses 21 and as the process continues the striking surfaces 20 of the blocks are protected by material retained in the cavities, and so wear on the striking surfaces is reduced as the material itself absorbs impact. However, wear does take place and eventually the striking surfaces 20 are unfit for further use. At this stage, the larger blocks are reversed to introduce fresh striking faces, and thus the lift of each block is doubled. It will be appreciated that the cost of a block according to the present invention will be more than but not double that of a single face block. Also, the inconveniences associated with ordering and transporting blocks are halved.

I claim:

1. An impact breaking or crushing machine comprising a series of rotary hammer heads and a plurality of attrition-resistant blocks detachably mounted so as to form an anvil surface for material which is impacted by the rotary hammer heads, some at least of the blocks being formed of S-shaped cross-section to provide on the striking surfaces recesses which act to retain some of the crushed or broken material thereby forming a protective layer for the anvil surface and to provide reverse surfaces with similar recesses to render the blocks reversible.

2. An impact breaking or crushing machine comprising a series of rotary hammer heads and a plurality of attrition-resistant blocks detachably mounted so as to form an anvil surface for material which is impacted by the rotary hammer heads, some at least of the blocks being formed of E-shaped cross-section to provide on the striking surfaces recesses which act to retain some of the crushed or broken material thereby forming a protective layer for the anvil surface and to provide reverse surfaces with similar recesses to render the blocks reversible.

3. An attrition resistant block for use in an anvil surface of an impact breaking or crushing machine, said block comprising a central striking portion having a medial plane and attachment projections at each end of

said central striking portion, said attachment projections being of less thickness than said central striking portion and being arranged symmetrically in relation to the medial plane of the central portion, said central striking portion having a pair of parallel faces which are laterally displaced from each other and lying at equal distances and on opposite sides of said medial plane, said central striking portion having a pair of parallel striking faces perpendicular to and intersecting the medial plane, each of said striking faces having at least one recess therein 10 to receive and hold material to be pulverized.

4. An attrition resistant block for use in an anvil surface of an impact breaking or crushing machine, said block comprising a central striking portion having a medial plane and attachment projections at each end of 15 said central striking portion, said attachment projections being of less thickness than said central striking portion and being arranged symmetrically in relation to the

5 medial plane of the central portion, said central striking portion having a pair of parallel faces which are laterally displaced from each other and lying at equal distances and on opposite sides of said medial plane, said central striking portion having a pair of parallel striking faces perpendicular to and intersecting the medial plane, one of said striking faces having at least two recesses therein to receive and hold material to be pulverized.
